(57) **CLAIM**

The ornamental design for a truck shelving system, as shown and described.

DESCRIPTION

FIG. 1 is a perspective view of a truck shelving system, showing our new design;

FIG. 2 is a front view thereof;

FIG. 3 is a right side view thereof, it being understood that the left side is a mirror image thereof;

FIG. 4 is a rear view thereof;

FIG. 5 is a top view thereof; and,

FIG. 6 is a bottom view thereof.

In the embodiment shown herein, the left and right sides are identical and mirror images of each other, and, therefore a view of only the right side is presented.
